(57) **CLAIM**

The ornamental design for a wrist wrap, as shown and described.

DESCRIPTION

FIG. 1 is a top, front and left side perspective view of a wrist wrap showing my new design;

FIG. 2 is a front elevation view thereof;

FIG. 3 is a rear elevation view thereof;

FIG. 4 is a bottom plan view thereof;

FIG. 5 is a top plan view thereof;

FIG. 6 is a left side view thereof; and,

FIG. 7 is a right side view thereof.

FIG. 8 is a rear, bottom and right side perspective view thereof.

The broken lines shown in the drawings illustrate portions of the wrist wrap that form no part of the claimed design.
